UNITED STATES PATENT OFFICE

156,082

DESIGN FOR A POURING SPOUT

Robert O. Ferguson, Bristol, Tenn., assignor of
one-half to Bristol Steel & Iron Works, Inc.,
Bristol, Va., a corporation of Virginia

Application April 5, 1948, Serial No. 145,519

Term of patent 14 years

(Cl. D58—17)

To all whom it may concern:

Be it known that I, Robert O. Ferguson, a citizen of the United States, and a resident of Bristol, in the county of Sullivan, and State of Tennessee, have invented a new, original, and ornamental Design for a Pouring Spout, of which the following is a specification, reference being had to the accompanying drawing, forming part thereof.

In the drawing:

Figure 1 is a top plan view of a pouring spout showing my new design,

Figure 2 is a bottom plan view thereof,

Figure 3 is a side elevational view, and

Figure 4 is a front elevational view.

I claim:
The ornamental design for a pouring spout, as shown.

ROBERT O. FERGUSON.
